(57) **CLAIM**

The ornamental design for an installation pilot device, as shown and described.

DESCRIPTION

FIG. 1 is a perspective view of an embodiment of an installation pilot device showing my new design;

FIG. 2 is a left side view thereof, the right side view being identical to the left side view;

FIG. 3 is a top view thereof;

FIG. 4 is a bottom view thereof;

FIG. 5 is a front view thereof, the rear view being identical to the front view;

FIG. 6 is a perspective view of an embodiment of an installation pilot device showing my new design; and,

FIG. 7 is a top view thereof, the left and right side views thereof being identical to FIG. 2, the bottom view thereof being identical to FIG. 4, and the front and rear views being identical to FIG. 5.

The broken line showing of FIGS. 6 and 7 is included for the purpose of illustrating portions of the installation pilot device and forms no part of the claimed design.
